UNITED STATES PATENT OFFICE.

EDGAR P. WEBSTER, OF BRIDGEPORT, CONNECTICUT.

ROLLER-BEARING.

1,326,239.

Specification of Letters Patent. Patented Dec. 30, 1919.

Application filed June 22, 1917. Serial No. 176,495.

To all whom it may concern:

Be it known that I, EDGAR P. WEBSTER, a citizen of the United States of America, and resident of Bridgeport, in the county of 5 Fairfield and State of Connecticut, have invented certain new and useful Improvements in Roller-Bearings, of which the following is a specification.

The present invention relates to improvements in roller bearings, and has for an object to provide a bearing of this type, which will operate in a more effective manner, and be so mounted as to be wear-resisting, and in which friction will be reduced to a high degree. Further objects are the production of a roller bearing which will be inexpensive, and with which the process of manufacture will be greatly simplified and facilitated. To this end, I propose to provide a bearing 20 in which the rollers will normally run practically free, the cage merely acting as a support and spacer therefor, and in which the wear from usage will be taken up in a manner as to not deter the proper functioning 25 of the bearing or reduce the advantage thereof.

With these and other objects in view, an embodiment of my invention is shown in the accompanying drawings, and this embodiment will be hereinafter more fully described with reference thereto, and finally pointed out in the claims.

In the accompanying drawings;

Figure 1 is a side view of the blanked out cylindrical holder or cage for the roller;

Fig. 2 is an end view of the same;

Fig. 3 is a side view showing the holder partially shaped;

Figs. 4 and 5 are front and rear end views 40 of the holder as formed in Fig. 3;

Fig. 6 is a longitudinal vertical section of the completed bearing;

Fig. 7 is a transverse vertical section of the same;

45 Figs. 8 and 9 are detail vertical and horizontal sections of the roller and the portion of the cage surrounding the same; and

Figs. 10 and 11 are side and end views respectively of the bearing, showing the same 50 mounted in inner and outer races.

Similar reference characters indicate corresponding parts throughout the several figures of the drawings.

Referring to the drawings, and more particularly to Figs. 1 and 2 thereof, the illustrative embodiment of my invention com-

prises a holder or cage 20, formed from a cylindrical member 21 slightly tapered, or the same may be straight, and provided intermediately its ends with substantially rectangular openings 22, and in its blanked out form shown in Figs. 1 and 2, has projections 23 and 24 at its end, in alignment with the openings 22. The upper corners of the openings 22, that is, at the enlarged end of the cage, are rectangular as at 25, the corners at the lower end being rounded as at 26. The corners of the projections 23 and 24 are angular, as at 27.

The projections 23 and 24 are bent inwardly as shown in Figs. 3 to 5, the projection 23 also being turned outwardly as at 28 to permit of insertion of the rollers, as hereinafter pointed out. The projections at each side are thereafter pointed by filing, or other suitable process, as clearly shown in Figs. 6 and 9, and are inserted in recesses 29 and 30 provided in the ends of the rollers 31, constituting trunnions for the rollers. These trunnions may be formed in any suitable manner, and the trunnions and openings may be of any suitable shape to carry out my invention.

The pointed projections at one side are first bent in, the rollers being engaged with the same, and then secured by bending in the projections at the other side. The dimensions of the openings 22 and the rollers are such that the sides of the rollers do not engage the sides of the openings.

The pointed projections engage the recesses 29 and 30 somewhat loosely, so that the rollers are permitted to move slightly in all directions, and revolve with the least amount of resistance or friction, so that the rollers while being held in spaced relation, run substantially free.

The roller is slightly tapered in the embodiment shown, and the upper or enlarged end is beveled as at 32 to the recess 29, while the lower end is flat.

In Figs. 10 and 11, I have shown my improved roller bearing inserted between an inner race member or ring 33, and an outer ring 34. In operation it will be noted that the surface of the rollers which engages the ring, is not resisted by the edges of the openings, and as the support upon the trunnion projections 23 and 24 is comparatively loose, very little friction is produced at these points. The device may be manufactured by simple and inexpensive processes.

I have illustrated a preferred and satisfactory embodiment of my invention, but it is obvious that changes may be made therein within the spirit and scope thereof, as defined in the appended claims.

I claim:

1. A roller bearing comprising an annular one-piece cage having spaced openings formed therein, rollers projecting through 10 said openings, and trunnions for the rollers projecting inwardly from the opposite edges of the cage and preventing contact of the cage body with the rollers.

2. A roller bearing comprising an annular 15 one-piece cage having spaced openings formed therein, rollers projecting through said openings, the body wall of the cage having extensions on its opposite edges inwardly bent in parallel relation to said wall and 20 forming trunnions to operatively engage the rollers at their ends and prevent frictional contact of the cage wall with said rollers.

3. A roller bearing comprising an annular one-piece cage having spaced openings

formed therein, rollers projecting through 25 said openings and formed with axially extending recesses at their ends, the body wall of the cage having extensions on its opposite edges inwardly bent in parallel relation to said wall, and engaged in said recesses to 30 provide trunnions operating to sustain the cage wall out of frictional contact with the rollers.

4. A roller bearing comprising an annular one-piece cage having spaced openings 35 formed therein, the body wall of the cage having integral extensions on its opposite sides extending inwardly to form trunnions, adapted to engage axial recesses in rollers 40 projecting through said openings of the body wall.

In testimony that I claim the foregoing as my invention, I have signed my name in presence of two subscribing witnesses.

EDGAR P. WEBSTER.
